Primary Examiner — Robert M Spear*Assistant Examiner* — Kendra L Hamilton(74) *Attorney, Agent, or Firm* — McGuireWoods LLP(57) **CLAIM**

I claim the ornamental design for a chain saw for cutting stone, as shown and described.

DESCRIPTION

FIG. 1 is a left-rear perspective view of the chain saw for cutting stone;

FIG. 2 is a front view of the chain saw for cutting stone shown in FIG. 1;

FIG. 3 is a rear view of the chain saw for cutting stone shown in FIG. 1;

FIG. 4 is a right side view of the chain saw for cutting stone shown in FIG. 1;

FIG. 5 is a left side view of the chain saw for cutting stone shown in FIG. 1;

FIG. 6 is a top view of the chain saw for cutting stone shown in FIG. 1; and,

FIG. 7 is a bottom view of the chain saw for cutting stone shown in FIG. 1.

The portions of the figures shown in broken lines depict environmental structure that form no part of the claimed design.
